T. SMOLINSKY,
WORK SUPPORT.
APPLICATION FILED AUG. 7, 1918.

1,306,782.

Patented June 17, 1919.

UNITED STATES PATENT OFFICE.

THEODOR SMOLINSKY, OF GARY, INDIANA.

WORK-SUPPORT.

1,306,782.

Specification of Letters Patent. Patented June 17, 1919.

Application filed August 7, 1918. Serial No. 248,703.

To all whom it may concern:

Be it known that I, THEODOR SMOLINSKY, a subject of the Emperor of Austria, residing at Gary, in the county of Lake and State 5 of Indiana, have invented certain new and useful Improvements in Work-Supports, of which the following is a specification.

My invention relates to work supports, and has for its primary object the provision 10 of improved means for supporting a metal plate or plates in the various positions necessary for hammering out round kettles and the like. A further object lies in the provision of adjustable features whereby the 15 supporting mechanism of the present invention may be readily adapted to the formation of kettles of various sizes and shapes.

My invention relates also to a novel method 20 of forming simultaneously a plurality of kettles of identical shape and substantially identical size that may be nested one snugly within the other.

Other objects and advantages of the invention will appear from the following description, taken in conjunction with the accompanying drawings which form a part of this specification and illustrate the preferred embodiment of the invention.

In the drawings:

30 Figure 1 is a top plan view of the work support, showing a metal kettle in practically completed form mounted thereon.

Fig. 2 is a side elevation thereof, and illustrates in dotted lines a tilted position of 35 the kettle being formed.

Fig. 3 is a vertical central section through a plurality of superposed malleable metal plates illustrating one step in the method of forming a plurality of kettles at one operation.

Fig. 4 is a similar section to that shown in Fig. 3 but taken when the plates shown in Fig. 3 have been formed into the nest of kettles above mentioned.

45 Reference numeral 10 indicates the base of my invention for supporting metal during hammering. At the rear of this base an upstanding post 11 carries the vertically disposed guide bearing 12 of a power hammer 13, the latter being shown only fragmentally at its lower, striking end which is vertically reciprocated by any suitable means in the bearing. The hammer 13 is positioned centrally above and spaced from the base, and 50 directly beneath it an anvil 14 is removably fixed in the base by, preferably, a tongue

and groove connection as indicated at 15. The upper surface of the anvil is concaved for shaping the particular kettle 16 shown in the drawings, but other anvils differently 60 hollowed may be substituted for the formation beneath hammer 13 of kettles of various shapes and sizes.

A toothed arm 17 projects forwardly from the base 10 and the lower end of a standard 65 18 is adapted to rest upon that arm and between any two of the teeth 19 thereof. From each side of the anvil 14 a substantially horizontal bracket 21 projects forwardly and is downbent at its forward end and bolted 70 to or in any other suitable manner bears upon the base, the rear ends of these brackets being removably bolted to the sides of the anvil as at 22. The brackets 21 are oppositely and horizontally apertured in a plurality of places for the reception of a pivot pin 23 in any pair of apertures 24. A work supporting yoke 25 has its lower ends pivoted upon the two pins 23 and its upper end slanting forwardly and upwardly and pivotally hooked about one of the rungs 26 projecting rearwardly from the standard 18. The apertures 24 being all forward of the anvil, the concave surface of the anvil being also slanted downwardly from back to front, 80 the metal being worked on is always supported partly on the anvil and partly on the two legs of the yoke 25.

85 In the operation of the work support, the upper end of the yoke is first hooked upon 90 one of the lower rungs 26 and the flat plate of metal placed on the anvil and yoke. As the action of the hammer on the anvil dents the plate, the latter is rotated on a vertical axis by hand and is also tilted as shown in 95 dotted lines in Fig. 2 to enable the hammer to beat the metal into the curvature desired. As the curvature of the plate increases the upper end of the yoke is elevated rung by rung about pivot pins 23 to provide constant support for the work. If a large kettle 100 is being made, the standard will be near the forward or outer end of arm 17 and the pivot pins will engage the forward apertures 24; if a small kettle is to be beaten out 105 the lower end of the standard will be positioned nearer the rear end of the arm and the pins will be inserted in apertures nearer the anvil; in Fig. 2 the support is seen adjusted for the formation of a medium sized kettle, and the relation of parts is that assumed 110 when the kettle is practically completed.

Owing to the concave character of the upper surface of the anvil and the fact that the hammer strikes against the said upper surface at its point of greatest depth, the continued action of the hammer increases the curvature of the metal. As this concave surface slants forwardly the yoke aids in preventing dislodgment of the work from the anvil under the blows of the hammer. It will be seen that the hook 28 on the upper end of the yoke opens downwardly so that the hook is readily shifted from one rung 26 to another. The three point suspension for the article being beaten out is found highly useful in the metal beating art where kettles and similar articles weighing from one hundred pounds up are being handled, the particular form of the support obtained between the two legs of the yoke and the anvil leaving the work free for easy turning in any desired direction.

My improved method of simultaneously forming a plurality of kettles at one operation is adapted for use with the above described work supporting apparatus. In that method a number of superposed malleable plates 31 are employed, their edges being substantially coincident. These, as a body, are placed upon a bottom plate 32 of larger diameter, the edge portion of the bottom plate being bent upwardly about the edges of the body of plates as at 33 and clenched down upon the latter as seen at 34 in Figs. 3 and 4. The laminated plate thus formed is treated as above described for a single plate by being placed upon the anvil and the yoke 25 and by beating it with hammer 13. Fig. 3 shows the laminated plate after the process of beating it has just started; Fig. 4 illustrates a nest of kettles completed by this process. When the beating of the laminated plate is completed, the edge portion 33—34 is removed from the outer layer or plate 32 leaving the several laminæ separable from each other, this edge portion holding the laminæ in fixed relation to each other during the beating operation.

While I have illustrated and described the preferred embodiment of the invention, it will be obvious that one skilled in the art

might make modifications thereof without departing from the spirit of the invention. I wish, therefore, not to be restricted to the precise embodiment shown, except in so far as the same is limited in the appended claims.

I claim:

1. A work support, comprising an anvil, a pair of legs pivoted at their lower ends adjacent the anvil, a standard upon which the upper ends of the legs rest, means on the standard permitting adjustment of the legs thereon, and means permitting adjustment of the standard.

2. A work support for power hammers, comprising an anvil positioned beneath the hammer, a pair of legs pivoted forwardly of the anvil on a substantially horizontal axis, and means permitting adjustment of the free ends of said legs at various heights with respect to the anvil.

3. A work support, comprising a base, an anvil mounted thereon, a notched arm projecting forwardly of the base, a pair of opposite legs pivoted to the base forwardly of the anvil, and a standard bearing at its lower end on said arm and adapted for connection at various heights with the free ends of said legs.

4. A work support, comprising a base, an anvil mounted thereon, and an easel the lower ends of the work supporting legs of which are pivoted on a common axis to the base adjacent the anvil.

5. A work support, comprising a base, an anvil mounted thereon and having a concaved upper surface slanting forwardly and downwardly, a yoke having the ends of its legs pivoted to the base so that the legs slant forwardly and upwardly in front of the anvil, an arm projecting forwardly of the base, and a standard bearing upon said arm and adjustable forwardly and backwardly thereon, rungs formed on said standard, and a hook positioned at the middle of said yoke for engagement with said rungs.

In testimony whereof I affix my signature.

THEODOR SMOLINSKY.
